UNITED STATES PATENT OFFICE.

THOMAS SHAW, OF LANSING, MICHIGAN, ASSIGNOR TO ATLAS DROP FORGE CO., OF LANSING, MICHIGAN, A CORPORATION OF MICHIGAN.

CRANK-TWISTING MACHINE.

Application filed September 26, 1923. Serial No. 664,930.

To all whom it may concern:

Be it known that I, THOMAS SHAW, a citizen of the United States, residing at Lansing, in the county of Ingham and State of Michigan, have invented a new and useful Improvement in Crank-Twisting Machines, of which the following is a specification.

In the making of crank shafts for automobile engines and other engines of a similar type having several cylinders, the cranks of which stand at an angle with each other, the crank shaft is first forged with the various throws in a parallel or opposite position and are twisted to the proper angle while hot. My invention relates to devices for performing this twisting operation, and its purposes are to make a device that shall be rigid in construction; that shall permit of a ready adjustment to secure with the utmost exactness the proper angles, and that shall be substantially automatic in operation.

The form which I have illustrated in the drawings is intended to be operated by steam or compressed air cylinders, but it is evident that it might be manually operated without departing from my invention. As constructed, the air is controlled by a hand valve, not shown.

I attain the purposes of the invention by the means shown in the accompanying drawings in which Figure 1 is a side elevation of my device. The full lines show the position of the parts just after the crank shaft has been introduced into the machine and clamped in place in the loading position. Fig. 2 is a vertical section taken on the line 2—2 of Fig. 4. That is, an outer set of rocker arms has been taken away, most of the machine frame or standard has been torn away and the various positions of a second and third set of rocker arms are indicated by full and dotted lines. Fig. 3 shows an elevation of the top position of the machine frame or standard. Fig. 4 shows a plan view of the various dies in the loading position designed to hold the forging to be operated on, the covers and cover clamps for these dies being removed. Fig. 5 supplements Fig. 2 by showing the position of two of the rocker arms at the end of the operat-

ing stroke. Fig. 6 is a detail section, on the line 3—3 of Fig. 2 which will be explained later. Fig. 7 shows a modification of the linkage and Fig. 8 shows a plan of the same. Fig. 9 shows a plan of the forging before twisting, all bearings and crank pins being in the same plane. Fig. 10 shows an end elevation of the crank when completed, with crank pins one hundred and twenty degrees apart.

Referring to the drawings, 1 is the main frame of the machine which is largely shown removed in the drawings for the purpose of illustrating the construction and operation. In the form shown in the drawings, five floating rocker arms, 11, 12, 13, 14, and 15 are employed. These rocker arms are hinged at their extremities to vertical connecting links, 16, 17, 18, 19, and 20. The rocker arms 14 and 15, and the connecting links 19 and 20 are omitted from all the figures except Fig. 4, for purposes of clearness, their construction and operation being precisely the same as rocker arms 12, and 11 and connecting links 17 and 16 respectively. The connecting links 16, 17, 18, 19 and 20 are also pivoted to rocker arms 21, 22, 23, and 24. Connecting links 19 and 20 are also pivoted to corresponding rocker arms, mounted on axes 26 and 10, mounted on the frame of the machine. The connecting links 18 are connected at their extremities to rocker arms 24, which are mounted to revolve about axes 25, which are secured to the sides of the rocker arms connected to the connecting links 17 and 19. The axes 25 are offset from the axes 26 a distance equal to the throw of the proposed crank shaft. Stops 27 and 36 are provided to limit the motion of the various rocker arms, and a bracket 41 is secured to the arm 24 to engage with the cross bar 40 on the reverse stroke, as will be more fully explained hereafter.

Dies 28 are mounted on the upper surfaces of the rocker arms 11, 12, 13, 14, and 15, adapted to receive the various parts of the shaft forging, and clamps 29 controlled by levers 30, which are furnished with friction rollers 37, are provided to lock the various parts of the shaft in position on the dies,

the inside surface of each of these clamps being formed to fit the corresponding portion of the shaft. Clamps 31 are also mounted on the frame of the machine to lock the shaft in position with reference to the frame and corresponding dies. The device is preferably operated by three cylinders of which two, 32 and 33, are shown in the drawings, a third cylinder is omitted from the drawings, its relative position and operation being exactly the same as cylinder 33. The device, however, as already stated, might be manually operated without departing from my invention. The extremities of the rocker arms operated by the connecting links 17 and 19, are connected to each other by a cross bar 40 so as to move together. The connecting rods 16 and 20, however, travel entirely independently of each other. Fig. 9 of the drawings shows the crank shaft forging ready for insertion into the machine. In this drawing 2-2 and 6-6 indicate the bearings, and 3-3, 5-5 and 7-7 the crank pins, 4 represents a chordal member of the shaft connecting the crank pins 3-3, and 5-5. In the complete forging, this member is not radial but is substantially a chord of the circle described by the crank pin. For this reason the bearings 2 in the forging are offset slightly from the bearings 6 and are brought back to position in the twisting operation in a manner which will be more fully explained hereafter. The rocker arms 21 are mounted on bearings 10 which are connected, for stiffness, by links 39 which in turn, are secured to the frame in any suitable manner. The rocker arms 24 are split through their whole length for convenience in assembling and are held together by bolts 38. The cylinders 32 and 33, are connected to the frame 1 by hinges 54 so as to oscillate. The piston rods 35 are connected to projections 42 on links 18 and 16. Figs. 7 and 8 show a modified construction of my device designed to give increased stiffness against the strain of operation. The frame of the machine is prolonged upward and inward as shown at 43 and the link 18 is prolonged upward to a somewhat higher position as shown at 51. The links 17 and 19 are also prolonged upward in the same manner. A substantially horizontal link 48, extends from the link 17 and is keyed by a key 44 to a bent shaft 49 which revolves in bearings 47 in the upward extensions of the frame 1. The offset in the shaft 49 is precisely equal to the throw of the crank forging and a bearing 52 is formed at the center, connected by a link 50 to the upward extension of the link 18. In this modification, when the link 18 is drawn downward by the action of the cylinder 32, the link 50 simply revolves on the bearing 52. Since the distance between the

centers of the link 50 is precisely the same as those of the rocker arms of the link 18, and its position is parallel to them, it will maintain precisely the same relative position and will hold the upper end of the link 18 in that position, during the first part of the stroke. When the links 17 and 19 start downward, however, the links 48 will revolve the shaft 49, giving a motion corresponding to the off-set of the axes 25 and 26, thus maintaining an exact parallelism in all the three links concerned and resisting the side strain caused by the cylinder 32 which tends to spring the link 18 outward. 80

In the modification shown in Figures 7 and 8, the lowest set of rocker arms may be dispensed with, their place being taken by the links 48 and 50 which, being connected with the vertical connection links 17, 18, and 19, give the same parallel motion as is given by the lower set of rocker arms 21, 22, 23, and 24; the only purpose of the two sets of rocker arms being to give this parallel motion and thus sustain the floating rocker arms in position. 90

The operation of my device is as follows:

As already stated the crank shaft is first forged with the various cranks parallel to each other; that is, in a plane form, but the function of my device is to twist the various crank arms so that the crank pins will stand at an angle, for six cylinder engines, of 120 degrees with each other, of course, the angle would vary with the number of 100 cylinders. 95

With all of the floating rocker arms in their loading position and the clamps open the hot forging is placed on the dies and all the clamps are locked by the levers 30. Steam or compressed air is then turned into the cylinders. While in actual operation, the cylinders might operate in any order or simultaneously, for convenience in explanation, I prefer to start with the action 110 of cylinder 32. This draws down link 18 carrying with it rocker arm 13. This acts on crank pins 7, raising and revolving them counter clock-wise through an angle of 60 degrees. The twisting comes on bearings 2 which are held stationary meanwhile. This is the position indicated by the full lines in Fig. 2. When this motion is completed the rocker arm 24 engages with the cross bar 40 connecting the rocker arms 17 and 19, and carries them along with it in its motion through an additional angle of 30 degrees until the rocker arm 22 engages the stop 27 as shown in Fig. 2. During this operation the twist comes on crank pins 3-3 which are held still. In the meantime the bearings 2-2, because of the off-set of the axes 25 and 26, will have been carried to a new position as indicated in Fig. 3, carrying with them crank pins 7-7 and 130 115 120 125

their corresponding cranks. This completes the change of the forging as to that portion of it between the chordal members 4-4. These members are held stationary at all times being grasped by the clamps 31 mounted on the frame of the machine.

The cylinder 33 and its corresponding cylinder, not shown, then come into action and raise the bearings 6-6, revolving them 10 through an angle of 30 degrees clock wise to the position shown in the dotted lines in Fig. 1, about their crank pins 5-5, which are held stationary meanwhile, thus completing the operation. An end view of the 15 shaft will then give the appearance shown in Fig. 10. In this position the bearings 6-6 and 2-2 will have been brought exactly into line with each other and the crank pins will stand at an angle of 120 degrees 20 with each other, the crank pins 3 and 5 being connected by the chordal members 4, while the crank pins 5 are connected to the bearing 6 by radial throws 53. All the clamps are then loosened and thrown back. 25 Air is then turned into the opposite end of the cylinders and the operation reversed. The links rise, carrying with them their corresponding rocker arms until the projection 41 engages with the cross bar 40, then 30 carries with it the rocker arms 22 until they engage the stop 36, thus locking the entire device in the open position ready to receive another forging.

I claim as my invention and desire to 35 secure by Letters Patent:

1. The combination in a device of the character described, of a main frame, provided at its upper extremity with clamps adapted to releasably hold a forging in position; a plurality of floating rocker arms 40 also provided with clamps adapted to releasably engage with said forging; links connected to the opposite extremities of each of said rocker arms for retaining said floating rocker arms in cooperative relationship to each other and to said first mentioned clamps, and means for revolving said rocker arms about their respective centers of revolution.

50 2. The combination in a device of the character described, of a main frame, provided at its upper extremity with clamps adapted to releasably retain a forging in position; a plurality of floating rocker arms 55 also provided with clamps adapted to engage with said forging; links connected to the opposite extremities of each of said floating rocker arms; parallel motion rocker arms supported on relatively fixed axes and 60 having their extremities connected to said links so as to give a parallel motion thereto and means for revolving said first mentioned rocker arms about their respective axes.

65 3. The combination in a device of the character described, of a main frame, pro-

vided at its upper extremity with clamps adapted to releasably retain a forging in position; a plurality of floating rocker arms also provided with clamps adapted to releasably engage said forging; links 70 connected to the opposite extremities of each of said floating rocker arms; a plurality of parallel motion rocker arms supported on said frame, all of said rocker arms having their extremities connected to said links 75 so as to give a parallel motion thereto; and a plurality of parallel motion rocker arms each of which has its axis mounted on one of said last mentioned rocker arms.

4. The combination in a device of the character described, of a main frame, provided at its extremities with clamps adapted to releasably retain a forging in position; a pair of rocker arms revolubly mounted on fixed axes on said frame; links connecting the opposite extremities of each pair of said rocker arms and a floating rocker arm hinged to the extremities of said links 80 and provided with clamps adapted to releasably engage with said forging. 85

5. The combination in a device of the character described, of a main frame provided at its extremities with clamps adapted to releasably retain a forging in position; two pair of rocker arms revolubly mounted on fixed axes on said frame; links connecting the opposite extremities of each pair of said rocker arms, and a floating rocker arm hinged to the extremities of each pair of 90 said links and provided with clamps adapted to releasably engage with said forging. 95

6. The combination in a device of the character described, of a main frame provided at its extremities with clamps adapted to releasably retain a forging in position; two pairs of rocker arms revolubly mounted on fixed axes on said frame; a pair of rocker arms revolubly mounted on axes connected to said first mentioned rocker arms; links connecting the opposite extremities of each pair of said rocker arms, and a floating rocker arm hinged to the extremities of each pair of said links and provided with clamps adapted to releasably engage with said forging. 100 105 110 115

7. The combination in a device of the character described, of a main frame provided at its extremities with clamps adapted to releasably retain a forging in position; two pairs of rocker arms revolubly mounted on fixed axes on said frame; a pair of rocker arms revolubly mounted on axes connected to said first mentioned rocker arms; two pairs of rocker arms revolubly mounted on axes attached to said frame outside of and concentric with said first mentioned axes; links connecting the opposite extremities of each pair of said rocker arms, and a floating rocker arm hinged to the extremities of each pair of said links and provided 120 125 130

with clamps adapted to releasably engage with said forging.

8. The combination in a device of the character described, of a main frame provided at its extremities with clamps adapted to releasably retain a forging in position; parallel motion rocker arms revolubly

10 mounted on fixed axes on said frame; parallel motion links connected to the free extremities of said rocker arms; and a floating arm hinged to said links and provided with a clamp adapted to releasably engage said forging.

THOMAS SHAW.
